UNITED STATES PATENT OFFICE

170,517

COLLAPSIBLE TUBE STAND

James Bateman, Kearny, N. J.

Application May 6, 1953, Serial No. 24,869

Term of patent 14 years

(Cl. D4—3)

To all whom it may concern:

Be it known, that I, James Bateman, a citizen of the United States, residing at 410 Belgrove Drive, Kearny, State of New Jersey, have invented a new, original, and ornamental Design for a Collapsible Tube Stand, of which the following is a specification, reference being had to the accompanying drawing, forming a part thereof.

Figure 1 is a side view of a collapsible tube stand showing my new design.

Figure 2 is a front view of the stand.

Figure 3 is a cross-section taken on line 3—3 of Figure 1.

I claim:

The ornamental design for a collapsible tube stand, as shown.

JAMES BATEMAN.
